ABSTRACT OF THE DISCLOSURE

Slide-fastener stringer having at one end a molded thermoplastic end stop adapted to block withdrawal of the slider and formed with a longitudinally extending guide groove for leading the slider onto the stringer and with at least one resilient formation projecting into the groove for deflection by the slider upon its mounting but engageable with it to prevent withdrawal. The end stop is also provided with a pair of ridges aligned with the coupling elements to form additional guides for the slider.

Our present invention relates to slide fasteners and, more particularly, to slide-fastener strips having end-stop members adapted to block displacement of a slider therebeyond in a fastener-opening and/or fastener-closing direction. The invention also relates to finished slide fasteners, i.e. slide-fastener strips provided with the slider, as well as to an improved method for making such slide fasteners.

Conventional slide fasteners generally comprise a pair of interconnectable slide-fastener halves each provided with a respective support band or "tape" and a fastener or coupling element extending longitudinally along one edge of the tape, the fastener elements being mutually disengageable and connectable by the movement of a slider along these elements in the fastener-opening and fastener-closing direction, respectively. The fastener elements, which may be continuously formed from a thermoplastic material (e.g. a linear polyamide such as nylon) can be of the helical or meandering types; the invention, however, also pertains to slide-fastener halves using a chain of discrete coupling members which form a longitudinal array constituting the coupling element. Coupling elements of the latter type are generally composed of metal. The support band or tape may consist of a fabric or a synthetic-resin thermoplastic foil although, for the present purposes, the fabric may also consist of thermally softenable synthetic-resin fibers. In conventional slide fasteners of these general types and those using metallic fastener elements, or nonthermally softenable tapes, end-stop members are generally provided at the so-called "upper" and "lower" extremities of the strip. The end-stop members are designed to prevent withdrawal of the slider from the fastening elements and thus engage the slider during the fastener-closing and fastener-opening movements thereof, respectively. In the slide fasteners of prior-art constructions, these end-stop members have frequently prevented the convenient mounting of the slider upon the fastener strip, especially when the slider is to be mounted more or less automatically. These members, moreover, prevent both the forward and backward displacement of the slider beyond the stops. Thus, the slider must be mounted upon the strip prior to the application of the end-stop members thereto. Such an arrangement is inconvenient especially when the slide-fastener strip is to be formed from a continuous band of interconnected slide-fastener halves, the individual strips being severed from this band and the upper and lower end-stop members being applied in spaced-apart rela-

2

tionship. A method of this type is described in the commonly assigned copending applications Ser. Nos. 472,593 and 473,003, filed concurrently herewith and entitled, Method of and Apparatus for Finishing Slide Fasteners, and Method of and Apparatus for the Production of Individual Slide Fasteners, respectively. The difficulties encountered when the end-stop members are applied to the slide-fastener strips prior to mounting the slider thereon, are increased manifold when the mounting is to be carried out automatically by, for example, devices of the type illustrated and described in these copending applications.

It is the principal object of the present invention, therefore, to provide an improved slide-fastener strip, which can be completed to constitute a slide fastener ready for use by mounting a slider thereon, permitting the slider to be drawn onto the fastening elements after the end-stop member or members are emplaced.

A further object of this invention is to provide slide-fastener strips of the character described having improved end-stop members at least at one end thereof.

Still another object of this invention is to provide an improved method of producing these novel slide-fastener strips.

25 A further object of this invention is to produce a complete slide fastener from which the slider cannot be unintentionally withdrawn past the end-stop members.

These objects and others which will become apparent hereinafter are attained in accordance with the present invention, by providing a slide-fastener strip having upper and lower end-stop members, preferably of a thermoplastic material and thermally bonded to the slide-fastener halves, wherein at least one end-stop member (occasionally referred to hereinafter as the "upper" member) is disposed at an extremity of the strip for blocking displacement of the slider in the fastener-closing direction, this member being formed with at least one and preferably two elastically deformable formations resiliently deflectable by the slider to permit the latter to be drawn onto the fastening elements past the end-stop member, but engageable with the slider to prevent the withdrawal from the elements.

45 Advantageously, the formation is integral (i.e. one piece) with the upper end-stop member, either the member or the formation being highly flexible; thus, according to a specific feature of this invention, the elastically deformable formation can be rendered more flexible than the remainder of the member by, for example, the heating step at which the formation is molded. The formation thus constitutes a pawl-like member which prevents removal of the slider over the end-stop member although it permits the slider to be drawn thereover without residual deformation of the pawl. It is, moreover, contemplated in accordance with the present invention to construct the slider in such manner that the portion thereof engageable with the elastically deformable formation may, at least in part, also be elastically deformable.

60 While the present invention can be embodied in various ways, it has been found that best results are obtained when the formations are of either of the two configurations discussed below. Thus, in one preferred construction of the elastically deformable formations, they are of toothed profile, in side view, so that they have a first flank of only slight inclination in the fastener-opening direction and a steep second flank confronting the slider upon the mounting thereof upon the emplacement of the slider. The sliders in use with conventional slide fasteners are those intended for use with the present invention and generally have, at their upper open ends, open sides forming with the longitudinally extending fastener elements and/or the plane of their support tapes, an acute angle in the fastener-opening direction. I have found it to be highly advan-

tageous, especially when the elastically deformable formation is of toothed configuration, to orient the formations at a corresponding angle to the fastener elements so that, upon slider-engagement blocking operation of the formation, the inclined sides of the slider abut in substantially parallel relationship the correspondingly inclined formation surfaces.

In the alternative construction of the formations, the end-stop member is provided with a pair of longitudinal guide grooves by means of which the slider is led onto the fastening elements; the elastically deformable formations in this case extend into the grooves and into the path of the slider traversing the latter.

Advantageously, the upper and lower end-stop members are composed of the same material and are applied with pressure and heat to the slide-fastener strip to form a thermal bond between the strip and the members. Preferably, the end-stop members are mounted upon a continuous slide-fastener band from which the individual strips are severed. In this case, the upper end-stop member of one strip, provided with elastically deformable formations as described above, and a further end-stop member of a next-adjacent and longitudinally contiguous strip to be formed upon severing of the strips between these members, are applied simultaneously and an incision made between the end-stop members. Thus both end-stop members can be formed integrally from a single foil as described and claimed in the above-identified applications, the elastically deformable formations being produced concurrently with the application of the foil to the slide-fastener strips. It is especially desirable to form the simultaneously applied end-stop members from a single foil, but with longitudinal spacing from one another so that a slot can be provided between the end-stop members for accommodating the slider and facilitating its mounting upon the slide-fastener strip. This technique is also fully described in the above-identified commonly assigned applications.

It will be apparent that the method and article described above constitute an improvement over prior slide-fastener constructions and techniques in that the mounting of the slider is permitted upon a slide-fastener strip previously provided with the end-stop members in spite of the fact that the end-stop members are designed to prevent displacement of the slider therebeyond in a direction tending to withdraw the slider from the fastening elements. The assembly of the slider is thus greatly simplified and the slide fasteners can be produced at reduced cost, with greater efficiency and a diminished expenditure of labor.

The above and other objects, features and advantages of the present invention will become more readily apparent from the following description, reference being made to the accompanying drawing in which:

FIG. 1 is a partial plan view of the upper end of a slide-fastener strip, according to the present invention, provided with an end-stop member with elastically deformable formations and of the lower end-stop member of an adjacent slide-fastener strip;

FIG. 2 is an enlarged cross-sectional view taken generally along the line II—II of FIG. 1 and showing the elastically deformable formations from the side;

FIG. 3 is a view similar to FIG. 2 of a modified pawl-like toothed formation suitable for use with the end-stop member of FIG. 1;

FIG. 4 is a longitudinal cross-sectional view taken along the line IV—IV of FIG. 1;

FIG. 5 is a view similar to that of FIG. 1 showing the slider about to be mounted upon the slide-fastener strip past the end-stop member provided with the deflectable formations;

FIG. 6 is a view similar to FIG. 1 illustrating another embodiment of the present invention; and

FIG. 7 is a cross-sectional view taken generally along the line VII—VII of FIG. 6.

In FIG. 1, I show the upper end of a slide-fastener strip 10 which is formed simultaneously with the lower end 30 of a slide-fastener strip with upper and lower end-stop members 17 and 39, respectively, as a continuous strip of interconnected slide-fastener halves passes a heat-bonding station as described in the aforementioned copending applications. The simultaneously applied instant members 17 and 39 are thereafter severed at 40. The slide-fastener strip 10 comprises a pair of slide-fastener halves each having a respective support band or tape 11, 12, for example, polyamide fabric. The longitudinally extending fastener elements, here shown as nylon spirals 13 and 14, are interconnected with the respective tapes 11 and 12 by stitched welts 15 and 16 forming guides for the slider 50 (FIG. 5). The thermoplastic end-stop member 17, which can also be composed of nylon-type polyamide, is formed integrally during its heatbonding to the slide-fastener strip with a pair of longitudinally extending ridges 18, 19, each aligned with respective fastener element 13, 14 for guiding the slider 50 onto the latter.

In addition, a pair of elastically deformable formations 21 and 22 are formed integrally (i.e. in one piece) with member 17 and can be inclined at the angle α to the fastener elements when the slider 50 is provided with similarly inclined sides 51 and 52 (FIG. 5). An aperture 20 may be punched in the slide-fastener strip to permit ready mounting of the slider. Elastically deformable formation 21 and 22, shown in an enlarged scale in FIG. 2, can be seen to be of toothed configuration with a slightly inclined ramp 23 facilitating the passage of the slider 50 in the fastener-opening direction (arrow A). The bridge of the slider 50 passes between the ridges 18 and 19 of the end-stop member and, in the usual manner, between the coupling elements 15, 16 of the stringer tape. A steep flank 24 is provided by the formations 21 and 22 to intercept the slider during reverse displacement of the latter to draw it off the fastening elements 13 and 14 beyond the end member 17. The formations 21 and 22 can be thermally softened so as to be more flexible (i.e. yieldable) than the balance of the end member 17 and are dimensioned so that the mounting of the slider and its displacement past these formations will not permanently deform them.

The lower end-stop member 39, which corresponds of course to the lower end-stop member of slide-fastener strip 10, is formed with a ramp 37 aligned with the ridges 18 and 19 and thus facilitates mounting of the slider 50 while a stiffening ridge 38 extends along the bottom of the slide fastener. End-stop member 39 is composed of thermoplastic material identical to that of end stop 17 and may be formed from a single foil therewith as described in the aforementioned copending applications. The end-stop member 39 is applied to the slide-fastener strip 30 whose tapes 31 and 32 are, in effect, continuous with the tapes 11 and 12 until severing at 40. Similarly, the fastening elements of spirals 33 and 34 are secured to the respective tapes by the stitched welts 35 and 36 (see FIG. 4).

From FIG. 3, it can be seen that the slider 50 has upwardly open surfaces 27 which are inclined to the plane of the tapes 11, 12, 31, 32 at an acute angle β corresponding to the angle defined between this plane and the steep flank 24' of the toothed formation 22'. The slightly inclined ramp 23' of the end-stop member 17' of this figure, corresponds, of course, to the ramp surface 23.

In FIG. 5, I show the slider 50 (in plan view) as it is drawn over the end-stop member 17 in the direction of arrow B. When the slider 50 clears the steep flanks 24 or 24', these flanks will constitute an abutment preventing further displacement of the slider off the fastening elements 13, 14, 33 and 34.

In the modification of FIG. 6, the upper end-stop member 60 is shown to be provided with a pair of ridges 62 and 63 forming guides for the sliders 50 and flanking a pair of guide grooves 70, 71 through which the slider

passes. On the opposite side of these grooves, a pair of longitudinally extending ridges 64 and 65 are provided, these latter ridges having elastically deformable formations 66 and 67 projecting into the grooves 70, 71 and thus into the path of the slider. Again, these formations can be somewhat softer and more elastic than the balance of the end-stop member 60 or of the same elasticity of the latter when the end-stop member is composed of a relatively soft thermoplastic material (e.g. polyethylene or nylon polyamide). The lower end-stop member 70 can be of the construction described in FIG. 1. The stop members of FIGS. 1-7 can be applied by the techniques described in the above-identified copending applications as the continuous slide-fastener band is displaced in the direction of arrow A, the sliders being applied automatically with a forward motion in the direction of arrow A or a reverse motion of the continuous band.

The invention described and illustrated is believed to admit of many modifications within the ability of persons skilled in the art, all such modifications being considered within the spirit and scope of the appended claims.

I claim:

1. A slide-fastener strip, comprising a pair of slide-fastener halves each having a respective support band and a fastener element extending along an edge of the band and matingly couplable with the fastener element of the other band upon the shifting of a slider along said elements in a fastener-closing direction, said elements being decoupled upon shifting of the slider in the opposite, fastener-opening direction; and an end-stop member of a thermoplastic material affixed to said strip at one extremity thereof for blocking displacement of said slider in said fastener-closing direction, said member being formed with at least one longitudinally extending guide groove for leading said slider onto said band, and with at least one elastically deformable formation projecting into said groove and resiliently deflectable by the slider to permit it to be drawn onto said elements past said member but engageable with the slider to prevent its withdrawal from said elements past said member.

2. A slide-fastener strip, comprising a pair of slide-fastener halves each having a respective support band and a fastener element extending along an edge of the band and matingly couplable with the fastener element of the other band upon the shifting of a slider along said elements in a fastener-closing direction, said elements being decoupled upon shifting of the slider in the opposite, fastener-opening direction; and an end-stop member of a thermoplastic material affixed to said strip at one extremity thereof for blocking displacement of said slider in said fastener-closing direction, said member being formed with at least one elastically deformable formation resiliently deflectable by the slider to permit it to be drawn onto said elements past said member but engageable with the slider to prevent its withdrawal from said elements past said member, said member being formed with a pair of ridges each generally aligned with a respective one of said elements for guiding the slider onto said strip.

3. A slide-fastener strip as defined in claim 2 wherein said formation is more flexible than the remainder of said member.

4. A slide-fastener strip as defined in claim 2 wherein said formation is a tooth projecting from said member

and having a first flank of slight inclination in the fastener-opening direction and a steep second flank confronting said slider upon the mounting thereof on said elements.

5. A slide-fastener strip as defined in claim 4 wherein a pair of said formations are provided on said member, each upon a respective one of said slide-fastener halves.

6. A slide-fastener strip as defined in claim 4 wherein the slider has an open side including an acute angle with said elements, said formation being disposed substantially at a corresponding angle for generally parallel contact with said side at said steep flank upon engagement of the slider therewith.

7. A slide-fastener strip, comprising a pair of slide-fastener halves each having a respective support band and a fastener element extending along an edge of the band and matingly couplable with the fastener element of the other band upon the shifting of a slider along said elements in a fastener-closing direction, said elements being decoupled upon shifting of the slider in the opposite, fastener-opening direction; and an end-stop member of a thermoplastic material affixed to said strip at one extremity thereof for blocking displacement of said slider in said fastener-closing direction, said member being formed with at least one elastically deformable formation resiliently deflectable by the slider to permit it to be drawn onto said elements past said member but engageable with the slider to prevent its withdrawal from said elements past said member, said member being provided with a pair of transversely spaced generally parallel guide grooves extending in said fastener-opening direction, said formation extending into one of said grooves.

8. A slide-fastener strip as defined in claim 7 wherein a pair of said formations are provided upon said member, each extending into one of said grooves.

9. A slide-fastener strip as defined in claim 7 wherein said slide-fastener halves are composed at least in part of a thermoplastic, said member being thermally bonded to said slide-fastener halves.

10. A slide-fastener strip as defined in claim 9, wherein said strip is provided with a further end-stop member of said thermoplastic material at a location remote from the first-mentioned member and thermally bonded to said slide-fastener halves for blocking displacement of the slider beyond said further member in the fastener-opening direction.

11. A slide-fastener strip as defined in claim 7 wherein said formation has a slider-engaging surface including an acute angle with the plane of said support bands and corresponding to the inclination of the open end of the slider, thereby permitting engagement of said slider with said formation with surface contact.
